BLANK STOCK

Henry W. Lyons, Portland, Oreg.

Application September 19, 1932, Serial No. 633,897

3 Claims. (Cl. 41—10)

This invention relates, in general, to blank stock used by wall paper hangers and wall decorators for the purpose of providing a smooth even surface to support wall paper or other wall decorative mediums, and the invention particularly relates to blank stock constructed from material, of a comparatively heavy weight and consistency, which is adapted for providing a smooth and even background when properly applied to a wall, so that it may support thereon various and sundry wall-decorating mediums, such as finely printed paper, fabrics, linoleums and thin veneer.

My invention consists in providing blank stock whose longitudinal edges form sinuous lines of a definite and precise formation. Each longitudinal edge consists of a series of uniform scallops which permit sheets of blank stock to be placed upon a wall so that their longitudinal edges mesh and become registerably aligned with respect to each other to form a multi-curved seam therebetween.

It has been and still is the custom to use either unbleached cloth sheeting, such as canvas or muslin, or thin blank stock comparatively light in weight and made of short-fibered materials. Each of these have objectionable features and salient disadvantages which prevent their effective use as a background or support for fine wall-decorating mediums.

It is a well-known fact that all plastered surfaces contain minute pores that are not satisfactorily closed by a surface paint. Also shrinking and expanding forces in the plaster, or the timbers, caused by variance in temperatures or vibrations created by various means, cause cracks in the plastered surfaces. It is obvious that when such conditions exist, the hanging of any fabric or wall paper on such a surface may result in its distortion, cracking or tearing. By the use of a blanking stock constructed in accordance with

my invention, the inherent tensile strength of said stock tends to counteract, stabilize and distribute over a greater area of the supporting wall any unusual strains and stresses caused by the cracking forces. This permits the laying of the finishing sheets over walls having relatively large cracks and lines therein than has heretofore been possible, without the cracks and lines becoming a disfigurement to the outer finishing sheet of material, that is to form the finished sheet.

It has heretofore been impossible to utilize relatively heavy long-fibered blank stock having parallel longitudinal edges because these edges, after the blank stock was applied to a wall, had a tendency to curl up in drying, since the shrinkage caused by the drying of the paste could not be dis-

sipated, arrested, controlled or directed. Furthermore, the parallel longitudinal edges often times permit a crack in the wall, starting either at or near the meeting edges, joint or seam, to follow this weak line, resulting in damage to the decorative medium. Also, the decorative medium is usually manufactured with parallel longitudinal edges, and these edges may sometimes fall at or near the meeting edges of the blank stock. This is not desirable at any time, but, by the use of my invention, the shrinkage or expanding forces are controlled and directed in such a manner that the edges cannot curl, it is impossible for the parallel edges of the decorative medium to meet the edges of the blank stock, and no fissure can follow down the multi-curved joint. By this construction the shrinking forces are directed toward the base of the tongues where the same are arrested and spent.

Where blank stock is hung of the type here outlined and disclosed there can be no possibility of a double welt occurring in the blank stock that shows through the outer finishing sheet and it will produce a much smoother job and one that will remain intact and in fine position with freedom from looseness and from edge peel, and freedom from wall cracks showing, that were in the wall before the blank stock and the outer sheet were laid.

One of the objects of the invention is to provide a wall covering made of paper material which has tongues formed with indentures therebetween, each tongue having an area across the lower portion thereof within which the inwardly directed forces of shrinkage are permitted to spend themselves without disturbing the outer properly located end of the tongue with respect to its companion tongue on the blank sheet complementary to it.

A still further object of my invention consists in providing a background upon which relatively thin veneer may be hung for providing a room having the semblance and appearance of being made and sealed with a wood surface.

An object of the present invention is to provide an improved blank stock in which the edges are so shaped that the sheets mutually support and complement each other at the regions where they meet in creating a smooth and even supporting surface which practically eliminates the risk of distortion or cracking of the wallpaper or other decorative medium, and, at the same time, an approximately air-tight intimate contact is formed between the blank stock and wallpaper or veneer.

A still further object of the present invention is to provide a blanking stock of strong and durable construction which may be readily applied and which will afford, when applied, a smooth, even surface upon which any decorative medium, such as wall paper, linoleum, paneled wood or veneer may be effectively and quickly applied.

Another object of my invention is to provide a blank stock which is adapted to arrest and control the shrinkage and expanding forces inherent in a plastered surface and to prevent fissures from spreading excessively, to arrest and control the movement of the blank stock itself and to prevent the edges of the decorating medium from falling adjacent the seam or edges of the blank stock.

The particular object of my invention is to overcome not only the disadvantages of the present type of blank stock and present type of cloth sheeting but also those disadvantages which have become apparent in the application of blank stock heretofore invented and to provide a blank stock made of heavy paper that is inexpensive, simple and durable in construction and that can be quickly and easily manufactured and installed without detriment or change to the decorative medium.

With these and incidental objects in view, the invention consists in certain novel features of construction and combination of parts, the essential elements of which are set forth in the appended claims, and in preferred form of embodiment of which is hereinafter shown with reference to the drawing which accompanies and forms a part of this specification.

In the drawing:

Fig. 1 is a perspective, end view of a room upon which blank stock of my new and improved design has been placed to illustrate the finishing sheet as having been placed over the blank stock with some of the outer coating broken away to show my sheet in use.

Fig. 2 is a plan view of a portion of the blank stock illustrating the sinuous edges that are disposed at the longitudinal edges of each edge of the blank stock.

Fig. 3 is a fragmentary, plan view of the abutting sheets of blank stock and illustrating the abutting edges in place that form the meeting or abutting edges of the blank stock.

Like reference characters refer to like parts throughout the several views.

I provide a sinuous line 1, upon the oppositely disposed longitudinal edges 2 and 3 of a sheet, or roll of blank paper or other material 4 forming thereby uniform scallops. The edges 5 and 6 meet to form tongues, as shown at 8 and 9, and the base of each tongue has the same contour as the apex of said tongues, as shown at 10 and 11; that is, the apex and the base of each tongue are

formed from identical segments of a circle. By this construction it will be seen that the tongues formed in the blank sheets or rolls are adapted to mesh with tongues of corresponding sheets, thereby forming a sinuous edge. The purpose of forming such an edge has been specifically set forth hereinbefore. This construction also produces a blank stock which will, when placed on a supporting surface, remain in a relatively fixed relation thereto and whatever expansion or contraction may result from the application of a binding medium such as paste, on each side of the blank stock will be directed toward the tongues and be dissipated or spent at the base of each of said tongues, thus preventing the possibility of injuring or distorting, in any way, the decorative medium 12.

While the embodiment herein shown and described is admirably adapted to fulfill the objects stated, it is to be understood that it is not intended to confine the invention to the one form of embodiment herein shown and described, as it is susceptible of embodiment in various forms, all coming within the scope of the claims which follow.

What I claim is:

1. Wall covering for the purposes described comprising a sheet of material having its opposite edges formed with tongues equally spaced apart in the direction of the length of said sheet, the tips of each tongue being formed on a radius and the sides of said tongues extending tangentially from said tip in angular relation to the longitudinal centerline of each of said tongues, and said sheet adapted to be placed alongside of other sheets of identical formation with the abutting tongues of all of said sheets in intermeshing relation with each other.

2. Wall covering for the purposes described comprising a sheet of paper formed along its edges with a plurality of integral tongues equally spaced apart throughout the length of the sheet, the tip of each tongue being formed on a radius and the sides of the tongue extending tangentially from the tip in angular relation to the longitudinal centerline of the tongue.

3. Wall covering for the purposes described comprising a sheet of paper formed along its edges with a plurality of integral tongues equally spaced apart throughout the length of the sheet, the tip of each tongue being formed on a radius and the sides of the tongue extending tangentially from the tip in angular relation to the longitudinal centerline of the tongue, and the corresponding sides of two adjoining tongues converging tangentially into a radius equal to the radius of the tip of the tongue.
